UNITED STATES PATENT OFFICE.

PERLE T. HAMBRIC, OF DRYTOWN, CALIFORNIA, ASSIGNOR OF ONE-HALF TO WILTON E. DARROW, OF SUTTER CREEK, CALIFORNIA.

CONCENTRATING APPARATUS.

1,100,971.

Specification of Letters Patent. Patented June 23, 1914.

Application filed May 19, 1913. Serial No. 768,619.

To all whom it may concern:

Be it known that I, PERLE T. HAMBRIC, a citizen of the United States, residing at Drytown, in the county of Amador and State of California, have invented new and useful Improvements in Concentrating Apparatus, of which the following is a specification.

This invention relates to an apparatus for concentrating the metalliferous particles of value-bearing ores, and pertains especially to a type of apparatus known as canvas plants.

The main object of an apparatus of this character is to effect an efficient primary concentration, to bring up the percentage of values from say fifty cents or one dollar a ton to four or five dollars a ton, so as to render profitable a further handling of naturally low-grade ores.

The object of this invention is to provide a simple, compact, easily operable and adjustable self-washing canvas plant, which is continuous and automatic in operation, and which is provided with means for evenly distributing the pulp over the various concentrating surfaces.

The invention consists of the parts and the construction and combination of parts as hereinafter more fully described and claimed, having reference to the accompanying drawings, in which—

Figure 1 is a plan view partly broken away, showing the separate concentrating surfaces and their pulp distributing flumes. Fig. 2 is a section of the vertically disposed distributing flume. Fig. 3 is a vertical cross section of the apparatus. Fig. 4 is an enlarged view of one of the distributing flumes.

Referring to the drawings: A indicates a central shaft, suitably journaled as at 2 and 3 in a stationary frame B. Secured as at 4 on the shaft is a frame 5, upon which is mounted in superposed planes as at 6 and 6' a series of concentrating surfaces 7 and 8 to which pulp or material being concentrated is delivered from the series of diverting flumes and distributing surfaces later to be described. Surrounding the upper shaft journal 2 is a stationary annular receiving launder 9, having three discharge pipes, 10-11 and 12, the pipe 10 being connected with a source of fresh water supply as at 13, while the pipes 11 and 12 are provided for the purpose of distributing the pulp into a

revolving annular distributor 14, suitably secured to the shaft A. The revolving distributor is divided into four separate compartments 15-16-17 and 18, each of which is connected with inclined flumes 15'-16'-17' and 18', respectively, which in turn are connected with vertically disposed distributor flumes 15a-16a-17a and 18a, which in turn are divided into four distributing ducts 19-20-21 and 22. The vertically disposed distributor being divided into the separate distributing ducts 19-20-21 and 22 are positioned so as to divert the main flow of each flume 15'-16'-17' and 18' to four separate series of upper and lower concentrating surfaces, the ducts 19 and 22 being connected by pipes 23 and 24 with flumes 25 and 26, from which the pulp is conveyed to distributing surfaces 27 and 28, and finally delivered and evenly distributed upon the upper concentrating surfaces shown at 7a and 7b. The vertical distributing ducts 20 and 21 are similarly connected with flumes 25' and 26', which convey the pulp to distributing surfaces and the lower series of concentrating surfaces 8a and 8b. From this it can be seen that the pulp discharged from the stationary distributor 9 into the separate chambers in the revolving distributor 14 is diverted through the flumes 15'-16'-17' and 18', and finally delivered to a set of upper and lower concentrating surfaces indicated by the numerals 7a-7b and 8a-8b. The tables or concentrating surfaces 7 and 8 are covered with canvas or other suitable material to which the heavier particles of ore and metal will cling, while the lighter gangue or waste material is allowed to discharge from the outer edge or periphery of the concentrating tables into annular launders 29 and 30, suitably supported circumferentially of the revolving structure in the stationary frame B.

The concentrating tables 7 and 8, composing the upper and lower series of concentrating surfaces, are constructed in any suitable manner, and are here shown as removably supported upon arms 7' and 8', which are pivotally secured as at 31 and 32 in standards 33, secured in the revolving frame 5. The frame is also provided with standards 33', having cross bars 33a, provided with adjustable bolts 33b with which the pivoted arms 7' and 8' contact, thus providing means for adjusting the inclined po-

sition of the concentrating tables 7 and 8; this being of considerable importance when handling various materials.

Referring to Figs. 1 and 4, it will be seen 5 that the main distributing flumes 15'-16'-17' and 18', together with the distributing surfaces 27 and 28, are provided with pulp deflectors 34, provided with flexible extensions 35. These are provided for the purpose of evenly distributing and diverting 10 the flow through the flumes and over the various distributing surfaces.

Suitably mounted, as at 35', in the stationary frame B is a hollow standard 36, provided with radially disposed inwardly extending perforated spray pipes 37 and 38, and suitably secured on the lower end of the standard 36 is a crank-arm 39, which is connected through a link 40 with a crank 41, 20 forming part of a shaft 42, suitably journaled in a bracket 43, secured in the stationary frame B. Secured upon this crank shaft is a pinion 44, which is so positioned as to intermesh with a gear 45, secured upon the main shaft A. The revolving motion of the shaft A will thus be transmitted through the gear 45, pinion 44, crank 41, connecting link 40 and rocker-arm 39 to oscillate the standard with connected spray 25 pipes 37 and 38, and cause these to swing in an arc over the various concentrating surfaces, as these pass the spray pipes in their revolution within the stationary frame B.

35 In operation, revolving movement is transmitted to the shaft A and connected frame 5, in which the various concentrating tables are mounted, through any suitable means, as a pulley 46. The pulp to be concentrated is delivered through a launder 47 to the stationary annular launder 9, from where it is discharged through the pipes 11 and 12 into the several compartments 15-16-17 and 18, as these pass below the distributing pipes 11 and 12. The pulp is then conveyed from each separate compartment to the distributing flumes 15'-16'-17' and 18', and diverted through the vertical ducts 19-20-21 and 22 to the separate upper and 40 lower concentrating tables 7 and 8, being evenly distributed by the pulp deflectors 34, the outer flexible ends of which may be adjusted from time to time to secure the even distribution desired.

45 Referring to Fig. 1 it will be seen that the pulp to be concentrated is only delivered to the concentrating tables during one-half of the revolution, or while the compartments in the revolving distributor 14 are passing below the distributing pipes 11 and 12, and that no pulp is delivered to the concentrating tables during the remaining half of the revolution. The cycle of operation will thus be as follows: For instance, tracing the path 50 of the chamber 17 during one revolution,

it will be seen that the pulp is delivered to the chamber 17 in the revolving distributor 14 while passing below the pipes 11 and 12, causing the pulp thus delivered to be distributed to the various upper and lower series of concentrating tables during this 70 part of the revolution. The moment the distributing chamber 17 passes below the pipe 10 it will be seen that no new material will be delivered to the concentrating tables 75 at this point, as fresh water for washing purposes is only discharged at this point. The chamber 17 will thus receive a charge 80 of fresh clean water equal in volume to that of the previously delivered pulp, this being delivered through the pipes 13 and 10 and distributed through the flume 17' and ducts 19-20-21 and 22 to the various upper and lower concentrating tables, where it serves to remove the remaining waste or gangue on 85 the tables. During the remaining quarter revolution of the concentrating tables within the frame, after the waste or gangue have been removed, it is desired to remove the balance, and it therefore becomes necessary 90 to prevent the admission of pulp to the tables. This is accomplished by leaving a blank wall in the stationary annular distributor 9 at the point 9^a, thus preventing either the admission of pulp or fresh water 95 to the concentrating tables. The remaining values adhering to the canvas surfaces of the tables, after the gangue or waste material has been entirely discharged, is removed by the action of the spray pipes 37 and 38, 100 which, as before described, swing in an arc about the standard 36. The arcular or oscillating movement of the spray pipes will thus cause every part of the surface to be acted on by the spray, which is discharged 105 with sufficient pressure to remove the values previously collected, and will thus cause these to be discharged over the edge or periphery of the several concentrating tables into separate sections in the receiving launders 110 29 and 30, indicated in Fig. 1. The separate value-receiving sections or launders produced by providing the partitions 30^a will separate the value-receiving compartments of the launders from the gangue or 115 waste-receiving sections of the annular launders 29 and 30. The values thus received may be collected from time to time or conveyed to a further receiving chamber, not here shown, by a pipe 30^b, while the gangue 120 or waste materials received in the annular launders 29 and 30 may be discharged at any suitable point, not here shown.

The revolving movement of the frame and concentrating tables 7 and 8 is only provided for the purpose of distributing the pulp to the concentrating table, removing the waste materials by washing, and collecting the concentrates by further washing; and they are not revolved with sufficient 130

speed to create centrifugal action for the purpose of assisting the flow of the pulp, sufficient flow being created by placing the various flumes and distributing surfaces at 5 a suitable incline, and further inclination or adjustment for inclination being secured by adjusting the angle of the supporting arms 7' and 8'. It is thus possible to considerably increase or decrease the flow of pulp over 10 the tables when handling various grades of material. The pulp thus delivered to the receiving launder is finally distributed by flowing through the inclined flumes and distributing surfaces to the various tables, 15 where the values and heavy particles of ore are collected on the fabric, while the gangue or waste materials are discharged from the outer edge of the tables into the annular collecting launders 29 and 30. The separation 20 of the worthless material from the more valuable material takes place during the passage of the tables in their revolution within the stationary frame, during the period that no fresh material is delivered on 25 the tables, the clear water from the pipes 13 and 10 being given an opportunity to remove the residue or gangue, while the spray pipes 37 and 38 are finally provided for the purpose of removing the collected values. 30 It is understood that the purpose of this apparatus is to make a rough or primary concentration, and is thus especially adapted to handle low-grade ores; the final product of concentration collected between the sections 30^a being of sufficient richness to warrant further concentration by more efficient methods.

The apparatus constructed as here shown is continuous in operation and requires little 40 or no attention when once adjusted, and very little power is consumed in revolving the table, as this is only moved with sufficient speed to permit the removal of the concentrates, as these are collected from the several 45 concentrating tables.

By arranging the tables in deck formation or superposed planes, as here shown, the maximum capacity is had in the minimum amount of space.

50 Having thus described my invention, what I claim and desire to secure by Letters Patent is:

1. In a concentrating apparatus comprising a revolving frame having a series of radially disposed superposed independent concentrating tables, a mechanism for subdividing and distributing the pulp comprising a stationary pulp receiving launder mounted above the frame, an annular distributing launder 55 centrally mounted in the frame and revolvable with same, radially disposed and downwardly inclined flumes connected with the annular distributing launder, vertically disposed flumes connected with the outer ends 60 of said flumes and divided into a plurality 65

of ducts, a series of distributing plates secured in the revolving frame adapted to deliver and distribute the pulp to the concentrating tables, and means for conducting the pulp.

2. A concentrating apparatus comprising a revolving frame having a series of radially disposed upper and lower decks of concentrating surfaces, a stationary pulp receiving launder mounted above the frame, an annular distributing launder mounted in the frame and revolvable with same, partition walls in the distributing launder forming several separate independent distributing chambers, radial pulp distributing flumes 70 connected with each chamber adapted to convey the pulp to the concentrating surfaces, pipes in the receiving launder adapted to deliver pulp to the several distributing chambers, a fresh water compartment in the receiving launder, and a pipe in said compartment adapted to deliver fresh water to the distributing chambers. 75

3. A concentrating apparatus comprising a revolving frame having a series of radially disposed upper and lower decks of concentrating surfaces, a pulp receiving launder mounted above the frame, means for conveying the pulp from said launder and distributing it over the upper and lower decks of 80 concentrating surfaces, a series of pipes extending over the concentrating surfaces, and means operated by the revolving frame for swinging the spray pipes in an arc over the concentrating surfaces to remove the concentrates. 85

4. In a concentrating apparatus, a revolving frame, a plurality of series of independent spaced superposed concentrating tables carried by the frame, said series of tables 90 being arranged in circular order, a distributor carried by the frame and arranged centrally of the space defined by said tables, a stationary launder mounted above the distributor, radial flumes extending from said 95 distributor, a vertical divided flume connected to each radial flume and arranged so as to be common to pairs of adjacent superposed tables, and an individual lateral flume for each of said pairs of adjacent superposed 105 tables, which connect with said vertical flumes and lead to the respective tables of said pairs of adjacent superposed tables. 110

5. In a concentrating apparatus, a frame, a pair of lower and a pair of upper tables 120 carried by the frame, a vertical flume common to all four of said tables arranged at the inner ends and extending across the inner sides thereof, said flume being divided into four independent ducts, a flume connected to the inner end of each table, said last named flumes being located on opposite sides of the vertical flume, independent means extending outwardly from the sides 125 of the flume for conveying material from 130

- the four respective ducts to the four respective flumes that are connected to the inner ends of the tables, and means to convey the material to each of the ducts.
- 5 6. In a concentrating apparatus, a frame, a table carried by the frame, spraying means mounted upon a vertical axis, and means for oscillating the spraying means on said axis across the table.
- 10 7. In a concentrating apparatus, a frame, a table carried by the frame, spraying means mounted upon a vertical axis, means to rotate the frame, and means for oscillating the spraying means on said axis across the table,
- 15 8. In a concentrating apparatus, a frame, a table carried by the frame, said means for oscillating the spraying means being operated by said frame rotating means.
- 20 9. In a concentrating apparatus, a frame, a table carried by the frame, a horizontal spray pipe extending over the table, a rotatably mounted hollow vertical standard connected to said spray pipe, means to rotate
- the frame, and means connected to said standard and rotating means for oscillating the standard to cause said horizontal spray pipe to move across the table.
- 10 9. In a concentrating apparatus, a rotary frame, a stationary pulp receiver above the frame, a distributor mounted beneath the receiver, tables on the frame, means for delivering pulp to the tables during one-half of the revolution of the frame, means for delivering water during the next quarter revolution, means to spray the tables, and means for oscillating the spraying means during the remaining quarter revolution.
- In testimony whereof I have hereunto set my hand in the presence of two subscribing witnesses.

PERLE T. HAMBRIC.
